UNITED STATES PATENT OFFICE.

BERNARD A. GEURINK, OF EAST CLEVELAND, OHIO, ASSIGNOR TO THE TRENKAMP STOVE AND MANUFACTURING COMPANY, OF CLEVELAND, OHIO, A CORPORATION OF OHIO.

WATER-HEATER.

980,095.

Specification of Letters Patent. Patented Dec. 27, 1910.

Application filed September 23, 1909. Serial No. 519,295.

To all whom it may concern:

Be it known that I, BERNARD A. GEURINK, a citizen of the United States, and a resident of East Cleveland, county of Cuyahoga, and State of Ohio, have invented a new and useful Improvement in Water-Heaters, of which the following is a specification, the principle of the invention being herein explained and the best mode in which I have contemplated applying that principle, so as to distinguish it from other inventions.

My invention relates to water heaters of the type frequently found in connection with hot water tanks for residential use. Heaters of this general type comprise a water container, a casing around the container, and a burner located below the same.

My invention relates in particular to the provision of a sectional water container of such an improved construction that the water may have free circulation through each section, and through the container as a whole.

An improved arrangement of connections whereby the water container may be drained whenever desired, is an additional feature of the heater.

The invention herein described and claimed is the same as that originally set forth in certain of the claims of my application for United States Patent Serial No. 494,982, filed May 10, 1909.

To the accomplishment of these and related ends, said invention, then, consists of the means hereinafter fully described and particularly pointed out in the following claims.

The annexed drawing and the following description set forth in detail certain mechanism embodying the invention, such disclosed means constituting, however, but one of various mechanical forms in which the principle of the invention may be used.

In said annexed drawing:—Figure 1 is a vertical central section of a heater embodying my invention, the water container proper being shown in side elevation; Fig. 2 is a transverse section of the container on the line 2—2, Fig. 1.

The heater comprises a water container A wherein the water is designed to be heated and thence passed on to a point of use, or to a suitable tank or like reservoir. This water container A is composed of a series of simi-

lar sections a superposed one above the other, their number being such as to provide a container of sufficient capacity for the particular requirement. Each section of said container comprises a central chamber a' . A plurality of chambers a^2 radiate from the central chamber, and the walls a^3 between such radiating chambers alternately approach within a greater and a less distance of the center of the section, whereby the tendency to clog at the center is overcome. The bottom walls of the several radiating chambers are inclined downwardly toward the center of the section, with the exception of one chamber a^5 in the lowermost section of the series. This lowermost chamber is constructed so that its bottom inclines in the opposite direction. This chamber is also provided with openings a^6 a^7 in its side and bottom, respectively; to the opening a^6 is connected a supply pipe A^2 , and with the opening a^7 is connected a drain pipe. The discharge pipe a^4 for the water after it has been heated by passage through the container, is connected with the center of the uppermost section of the container in the usual fashion. Below the lowermost section of the series will be placed a burner B adapted, generally, for use with gas as a fuel. A casing D of general cylindrical form surrounds the water container.

The water container is supported by a suitable stand C. Fitted on this stand is a bracket c having its outer end formed with a vertically disposed pipe c' . This pipe c' is designed to be connected with the opening a^7 in the bottom section of the container and thus serves as a drain pipe. The lower end of this pipe may be provided with a plug as shown, or with a pet-cock. Extending inwardly from the pipe portion of the bracket is a short arm c^2 with horizontally disposed projections. It is designed that the burner shall have depending lugs on its under side adapted to engage the horizontal projections on the arm c^2 , which thus serves to partially support and center the burner. Extending outwardly also from the pipe section of the bracket, are two vertically spaced flanges c^3 . Between these flanges are hinged two intergeared casing sections of semi-cylindrical form, which are thus adapted to swing in a horizontal plane. These two sections when closed, serve to inclose the burner B.

It will be clearly seen that the improved form which I give to each of the series of sections of the water container, allows of an extremely free circulation through the container. This form effectively provides against any clogging at the center of the section, and the entire container, including each individual section thereof, may be quickly and efficiently drained of its contents through pipe c' .

Other modes of applying the principle of my invention may be employed instead of the one explained, change being made as regards the mechanism herein disclosed, provided the means stated by any one of the following claims or the equivalent of such stated means be employed.

I therefore particularly point out and distinctly claim as my invention:—

1. In a water heater of the class described, a water container made up of a plurality of centrally-connected sections, each section comprising a central chamber and a plurality of chambers radiating therefrom, the bottom walls of such radiating chambers inclining downwardly toward the center of the section, with the exception of the lowermost section of the series, such lowermost section having a radiating chamber inclining in the opposite direction.

2. In a water heater of the class described, a water container made up of a plurality of centrally-connected sections, each section comprising a central chamber and a plu-

rality of chambers radiating therefrom, the walls between such radiating chambers alternately approaching within a greater and less distance of the center of the section, and the bottom walls of such radiating chambers inclining downwardly toward the center of the section, with the exception of the lowermost section of the series, such lowermost section having a radiating chamber inclining in the opposite direction.

3. In a water heater of the class described, a water container made up of a plurality of centrally-connected sections, each section comprising a central chamber and a plurality of chambers radiating therefrom, the walls between such radiating chambers alternately approaching within a greater and less distance of the center of the section, the bottom walls of such radiating chambers inclining downwardly toward the center of the section with the exception of the lowermost section, such lowermost section having a radiating chamber inclining in the opposite direction and provided with an opening in its side and bottom respectively, and supply and drain connections for such side and bottom openings, respectively.

Signed by me this 18th day of Sept., 1909.

BERNARD A. GEURINK.
